UNITED STATES PATENT OFFICE

ARBA G. WILLIAMSON, OF CARNEGIE, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRACK CIRCUIT SYSTEM

Original application filed February 3, 1927, Serial No. 165,603. Patent No. 1,807,330, dated May 26, 1931.

Divided and this application filed February 19, 1931. Serial No. 516,886.

The present invention relates to track circuit systems, and this application is a division of one filed February 3, 1927, Ser. No. 165,603, now Patent No. 1,807,330, dated May 26, 1931.

This invention has for its main object and feature the provision of simple and effective means whereby the entry of a train in a track section will place a current of a given character, such as an alternating current derived from a local source of direct current, on the rails of the section. Such current may, of course, be used for any purpose desired, such as the control of a train travelling over the track section.

In the accompanying drawing the invention is disclosed, in a concrete and preferred form, in a diagrammatic view showing a traffic track and wayside elements associated therewith.

1 and 2 indicates traffic rails arranged in blocks or sections W, X and Y by means of insulation 3. The normal direction of travel is indicated by the arrow. The usual track circuit may be of any suitable character, and is here shown as being supplied with current from battery 316 connected to the rails, at the outgoing end of the section, by leads 326 and 327, armatures 330 and 331 and back contacts 318 and 319. At the other (ingoing) end of the section or block is the usual track, relay 151 with an exponent denoting its block location. 332 indicates a battery forming part of a normally open circuit that includes motor 320, interrupter 321, armatures 333 and 334 and primary 322 of a transformer T_x.

The secondary 323 of the transformer is included in a normally open circuit that comprises wires 324 and 329, front contacts 325 and 328, armatures 330 and 331 and leads 326 and 327. 317 indicates a normally deenergized relay that controls armatures 330, 331, 333 and 334, and it will be seen that, so long as this relay is deenergized, current is supplied from battery 316 to the rails and to track relay 151_x, but that the circuit that includes secondary 323, as well as the circuit that includes primary 322, is open. Relay 317 is energized by a circuit including wire 335, 50 armatures 336 and 337 and back contact 338

and front contact 339. Track relay 151_x controls armature 336 and track relay 151_y controls armature 337. It will now be seen that under normal conditions (when there is no train in sections X and Y) track relays 151_x and 151_y will both be energized and consequently relay 317 will be deenergized owing to the fact that armature 336 is up. If now a train enters section X from section W, track relay 151_x will be deenergized thereby dropping armature 336 and in consequence (provided track relay 151_y is energized) relay 317 will become energized thereby picking up its armature and rupturing the connection from battery 316 to the rails, but closing the two circuits that include primary 322 and secondary 323 of transformer T_x. This will cause current to flow from battery 332 to motor 320 and interrupter 321, and the interrupted current will energize primary 322. This, in turn, will induce an alternating current in secondary 323 which will be supplied to the rails where it can be picked up by the train or otherwise utilized. If, however, a train is in section Y when a train enters section X from section W, then track relay 151_y will be in its deenergized condition and consequently armature 337 will be down thereby preventing the energization of relay 317. If section Y is unoccupied and a train enters section X from W when another train is already in section X, then the train so entering will receive no current from the rails because all the current will have been shunted by the first train.

I claim:

1. A track circuit system comprising: a track section having traffic rails; a circuit including a source of direct current, a motor, an interrupter and a transformer; and means to supply current from the transformer to the rails of the section when a train enters said section.

2. A track circuit system comprising: a track section having traffic rails; a normally open circuit including a source of direct current, a motor, an interrupter and a transformer; and means to close said circuit when a train enters said section.

3. A track circuit system comprising: a

- track section having traffic rails; a circuit including a source of direct current, a motor, an interrupter and the primary of a transformer; a circuit including the secondary of the transformer, and means to supply current from the secondary of the transformer to the rails of the section when a train enters said section.
4. A track circuit system comprising: a track section having traffic rails, a normally open circuit including a source of direct current, a motor, an interrupter and the primary of a transformer; a circuit including the secondary of the transformer, and means to close the first circuit and to supply current from the secondary of the transformer to the rails of the section when a train enters said section.
5. A track circuit system comprising: a track section having traffic rails; a normally open circuit including a source of direct current, a motor, an interrupter and the primary of a transformer; a normally open circuit including the traffic rails of the section and the secondary of the transformer, and means to close both circuits when a train enters the section.
6. A track circuit system comprising: a track section having traffic rails; a circuit including a source of direct current, a motor, an interrupter and the primary of a transformer; a normally open circuit including the traffic rails of the section and the secondary of the transformer, and means to close said second circuit when a train enters the section.
7. A track circuit system comprising: a track section having traffic rails; a circuit including a source of direct current, an interrupter and a transformer; and means to supply current from the transformer to the rails of the section when a train enters said section.
8. A track circuit system comprising: a track section having traffic rails; a normally open circuit including a source of direct current, an interrupter and a transformer; and means to close said circuit when a train enters said section.
9. A track circuit system comprising: a track section having traffic rails; a circuit including a source of direct current, an interrupter and the primary of a transformer; a circuit including the secondary of the transformer, and means to supply current from the secondary of the transformer to the rails of the section when a train enters said section.
10. A track circuit system comprising: a track section having traffic rails; a normally open circuit including a source of direct current, an interrupter and the primary of a transformer; a circuit including the secondary of the transformer, and means to close the first circuit and to supply current from the secondary of the transformer to the rails of the section when a train enters said section.
- of the section when a train enters said section.
11. A track circuit system comprising: a track section having traffic rails; a normally open circuit including a source of direct current, an interrupter and the primary of a transformer; a normally open circuit including the traffic rails of the section and the secondary of the transformer, and means to close both circuits when a train enters the section.
12. A track circuit system comprising: a track section having traffic rails; a circuit including a source of direct current, an interrupter and the primary of a transformer; a normally open circuit including the traffic rails of the section and the secondary of the transformer, and means to close said second circuit when a train enters the section.
- Signed at Swissvale, in the county of Allegheny, and State of Pennsylvania, this 17th day of February, 1931.
- ARBA G. WILLIAMSON.
